W. H. J. Fraylock

UNITED STATES PATENT OFFICE.

CHARLES G. TAYLOR, OF HARTFORD, CONNECTICUT.

COMBINATION-TOOL.

No. 839,228.

Specification of Letters Patent.

Patented Dec. 25, 1908.

Application filed July 11, 1908. Serial No. 325,849.

To all whom it may concern:

Be it known that I, CHARLES G. TAYLOR, a citizen of the United States, residing at Hartford, in the county of Hartford and State of Connecticut, have invented certain new and useful Improvements in Combination-Tools, of which the following is a specification.

This invention relates to a tool-carrying device for accomplishing a number of different results—for instance, the removal of corks from bottles, of the usual corrugated caps from bottles, and the opening of sheet-metal cans of any form.

Primarily the object of the invention is the provision of what is known as a "combination-tool" for accomplishing the results mentioned, while a further object of the invention is the provision of a device of peculiar formation which may be utilized as a can-opener or as a device for removing the caps of bottles or other receptacles, as will herein-after be described.

In the accompanying drawings, Figure 1 is a perspective view of an implement involving the features of my invention. Fig. 2 is a perspective representation of the implement when employed as a can-opener. Fig. 3 shows the tool employed as a corkscrew. Fig. 4 is a side elevation illustrating how the improvement is utilized in removing the caps or closures of bottles, and Fig. 5 is an end view of the free end of the handle.

Like numerals designate similar parts throughout the several views.

Referring to the drawings, the numeral 5 indicates a handle composed of a metallic strip folded to form a loop 6, the arms of said strip being slightly offset at 7 to afford parallel walls, between which is pivoted on a rivet or other securing device 8 a corkscrew 9, the manner of the use of which is shown in Fig. 3. Forward of the offset part 7 the arms of the handle are brought more closely together at 10, and between them is secured, by rivets 12 or other means, a blade 13 of peculiar formation, said blade having a curved outer surface 14, terminating at its upper side in a hook 15, adapted to be received beneath the corrugated flange of a bottle closure or cap 16, as illustrated in Fig. 4. This blade is projected forward, as illustrated at 17, and is beveled at 18 to form a knife 19, commencing at the point 20 of the blade and terminating in a shoulder 21, which affords suffi-

cient width of material to enable the blade to be secured in position by the rivets 12, said wide portion being recessed at 22 to form the hook 15.

In advance of the part 10 of the handle the arms of the strip are brought together and are riveted at 23, and the free ends thereof are deflected at right angles, as at 24, and are cut away on their under edges at 25 to afford a seat to receive the edge of a can, as illustrated in Fig. 2 and Fig. 5.

From what has been stated it will be seen that a combination-tool of simple construction and readily available for accomplishing any of the purposes for which it is designed is provided.

It will also be evident that when the peculiarly-shaped blade 13 is employed as a device for removing the caps or closures of bottles it will be placed in the position illustrated in Fig. 4 the reverse of that shown in Fig. 2, where it is utilized as a can-opener.

While a corkscrew is shown as conveniently pivoted between the arms of the handle, it is obvious that a tool of different character may be substituted therefor, if desired.

Changes may be made without departure from the invention, which is not limited to the precise construction shown and described.

Having thus described my invention, what I claim is—

1. A curved plate having a hook at one end, and a lateral extension provided with a cutting edge on its under side, combined with a handle, and with means for holding and securing said plate, said handle being provided with a fulcrum at its inner end, substantially as set forth.

2. A device of the class described comprising a bowed handle, a blade having a hook at one end and an extension at its other end, said extension having a cutting edge, and means for securing said blade between the arms of the bowed handle.

3. A device of the class described, comprising a loop-shaped handle having arms extending from the ends of the loop, said arms being provided with offset portions, and shaped intermediate said offset portions to receive between them a blade; a blade having a hook at one end, and an extension at its opposite extremity, said extension having a cutting edge; means for securing said blade between the offset portions of the handle, the

ends of said handle being brought closely together beyond one of the offset portions and there united, and the extremities of said ends having lateral extensions, substantially as set forth.

4. The combination, with a handle composed of a single strip bent upon itself to form a loop at one end, and united at its other end, and laterally extended to form arms to engage a can, of a blade located be-

tween the strips of the handle, and having a hook at one end, and a cutting edge at its opposite extremity.

In testimony whereof I affix my signature in presence of two witnesses.

CHARLES G. TAYLOR.
